UNITED STATES PATENT OFFICE.

LOUIS T. MEDHOLDT, OF ROCKFORD, ILLINOIS, ASSIGNOR TO MATTISON MACHINE WORKS, OF ROCKFORD, ILLINOIS, A CORPORATION OF ILLINOIS.

CUTTER HEAD.

Application filed March 20, 1925. Serial No. 16,902.

The invention relates to cutter heads of the type used in moulders and other wood working machines, and the object of the invention, generally stated, is to provide a head of improved construction whereby the cutter blades may be more effectually mounted in the head than heretofore.

A common form of cutter head at present in use in the wood working art is a substantially rectangular head providing upon its outer sides clamping faces for the cutter blades, the latter being secured upon said faces by means of bolts having flat heads entered in undercut or T-slots formed in the faces of the head. Considerable difficulty has been experienced with heads as thus constructed because the blades are subjected to severe strains and being unsupported by the body or head are frequently broken loose from the head, the clamping bolts giving away under the strain.

Various efforts have, in the past, been made to remedy this difficulty, but such efforts have not, so far as I am aware, met with success. My invention therefore has for its especial aim the solution of the difficulty in a thoroughly practical manner. Thus it is desirable not only that a rigid support or backing be provided in the body of the head for each blade, but it is desirable that the strains incident to clamping each blade in position in the head be confined to the side wall of the head to which it is secured so as to avoid distorting the head. I attain this result by my invention which consists generally in making the head in the form of a hollow body having interior dimensions transversely of the body substantially greater than the diameter of the supporting spindle passing through the body; providing slots in the body to receive the blades with their inner ends lying against the inner faces of the side walls of the body; and rigidly securing the blades upon said inner faces by means of clamping bolts entered through the blades and the side walls with which they respectively engage. By this arrangement, each of the blades is firmly supported or backed adjacent its cutting edge by the rigid side walls, and the strains incident to clamping each blade in position are confined to the side wall to which it is clamped. A further advantage is that the inner ends of the blades and the major portion of the clamping means are disposed sub-

stantially nearer the axis of the cutter than with the prior construction above referred to, with the result that it is possible to operate the head at much higher speeds without subjecting the same to undue strain due to the action of centrifugal force.

In the accompanying drawings I have shown my invention as applied to a cutter head which is one instance comprises a hollow body having four side walls formed integral with opposite end walls and in another instance comprises a hollow body having two opposed side walls formed integral with opposite end walls and two side walls formed separately from the end walls so as to be removable at will, the separable walls being securely held in interengaging relation with the end walls. In a copending application Serial No. 11,059, filed February 24, 1925, I have shown a cutter head construction in which four side walls are formed separately from the end walls, but clamped together into a rigid unit. Other embodiments of the invention with various changes in construction and arrangement may, it is contemplated, be produced by those skilled in the art without departing from the spirit and scope of the invention as expressed in the appended claims.

Figure 1 of the drawings is a fragmentary side elevational view of a cutter head having four side walls integral with opposite end walls.

Fig. 2 is a longitudinal sectional view through the same.

Fig. 3 is a transverse sectional view taken approximately in the plane of line 3—3 of Fig. 1.

Fig. 4 is a similar view but taken in the plane of line 4—4 of Fig. 1.

Fig. 5 is a fragmentary side elevational view of a cutter head having two side walls formed integral with the end wall and two side walls formed separately therefrom.

Fig. 6 is a transverse sectional view taken approximately in the plane of line 6—6 of Fig. 5.

Fig. 7 is a similar view but showing the separable wall sections removed.

Fig. 8 is a detached elevational view of a part of the means for clamping the head upon the spindle.

Referring first to the form shown in Figs. 1 to 4, the cutter head comprises a hollow body having opposite end walls 10 and 11 and

apertured centrally thereof to receive the supporting spindle 12 and the clamping means whereby the head is secured to the spindle. Inasmuch as this clamping means 5 forms, *per se*, no part of this invention, it may be described briefly as comprising a sleeve 13 (Fig. 8) having a conical head 14 at one end adapted to engage with a tapered bearing surface 15 in the end wall 11 of the head. The sleeve is slotted throughout its 10 length so as to be contractible and at the end opposite the head 14 it is screw-threaded as indicated at 16 to receive a clamping nut 17 between which and the end wall 10 is interposed a split conical ring 18 bearing against a tapered surface 19 formed in the wall 10 of the head. Tightening the nut 17 serves to clamp the head centrally upon the spindle 12.

20 I have herein shown the body of the head as having an outer surface generally cylindrical in form. The end walls are connected by four side walls 20, 20^a, 20^b and 20^c. While the outer sides of these walls are circular or arcuate in form the inner sides are 25 preferably shaped to provide flat inner clamping faces 21. These in the present instance form a substantially rectangular chamber the transverse dimensions of which are substantially greater than the diameter of the spindle 12, thus providing a space between the spindle and each of the faces 21 for accommodating the cutting blades and their securing means.

30 Leading from the interior of the head outwardly through the body at one longitudinal edge of each side wall is an approximately tangential slot 22 having one wall formed as a continuation of the clamping 35 face 21, and upon each clamping face 21 may be secured a cutting blade 23 the outer end portion of which projects through a slot 22 slightly beyond the outer periphery of the head.

40 The means for clamping the connecting 45 blades 23 upon their clamping faces 21 preferably comprises, in each case, a bolt 24 entered through an elongated opening or slot 50 25 in the side wall. The blades have their inner ends provided with longitudinal slots 26 for receiving the bolts 24, and preferably the bolt is passed from the interior of the 55 head outwardly through the side wall, the outer end being provided with a nut 27 which together with a washer 28 is counter-sunk in an elongated recess 29 formed in the outer face of the side wall. The head 30 of the bolt is made relatively flat and the sleeve 13 may be cut away upon four sides as 60 shown clearly at 31 (Fig. 4) to provide increased space for the head 30 of the bolt.

65 It will be seen that by this construction a firm support or backing in the body of the head is provided for each blade, near its cutting edge, and that the blade is clamped in

position in such a way that the clamping strains are confined entirely to the side wall to which it is secured, thus avoiding any possible distortion of the head.

Referring now to Figs. 5 and 6, the construction is generally similar to that shown in Figs. 1 to 4 except that in this instance only the side walls 20 and 20^b are formed integral with the end walls, the side walls 20^a and 20^c being made in separate approximately segmental sections interengaging at 70 opposite ends with the end walls and secured in position by means of longitudinal clamping bolts 32. In order that these removable wall portions may be securely held in position their opposite ends are shaped to engage in grooves 34 having inclined faces 35 arranged to prevent radial outward movement of these wall sections. The latter are slid edgewise into place and securely clamped 75 against movement in the grooves by means of the bolts 32 which are entered through elongated grooves 36 in the inner faces of the wall sections and near one edge thereof. The opposite ends of the bolts pass through 80 suitable apertures 37 in the end walls 10 and 11.

It frequently is desirable to employ in the cutter head two blades only. It will be observed in this connection that the construction shown in Figs. 5 and 6 lends itself readily to the use of two blades, it being only necessary to remove the separable sections 20^a and 20^c, the clamping of each blade upon its clamping face being entirely 90 independent of adjacent side walls.

I claim as my invention:

1. A high speed cutter head comprising, in combination, a hollow body having rigid end and side walls and adapted to be mounted upon a supporting spindle, the interior dimensions of said body being substantially greater than the diameter of the spindle, cutting blades having their inner ends lying within the body and their outer ends projecting therefrom, there being openings in the body to permit said blades to pass therethrough, and radial clamping bolts entered perpendicularly through said blades and the side walls of the body for clamping the 105 blades rigidly upon the inner faces of said side walls, the heads of said bolts being disposed between the spindle and the blades upon the inner faces of the body so that the spindle limits inward movement of the 110 bolt.

2. A cutter head of the character described comprising a hollow body having end walls centrally apertured to receive the supporting spindle, and a plurality of side walls 115 rigid with the end walls, the inner faces of said side walls extending to a point close to the adjacent blade and providing clamping surfaces for a plurality of cutter blades, said body having longitudinally extending 120

slots therein one wall of each of which is flush with the inner face of a side wall, blades entered through said slots and lying against said inner faces of the side walls, 5 and bolts entered radially through the side walls for clamping the blades in position upon said clamping surfaces.

45

3. A high speed cutter head comprising a hollow body, blades projecting outwardly

10 through the body, the body having end walls and side walls with inner faces against which the inner portions of the blades may be secured, and means passing through the side walls of the body for clamping the

15 blades against said clamping surfaces, alternate side walls of the body being formed integral with the end walls and the remaining side walls being formed separately therefrom and detachably secured thereto.

20

4. A high speed cutter head of the character described comprising, in combination, a hollow body having a pair of end walls and a pair of side walls formed integral with the end walls at opposite sides of the

25 head, each of said side walls providing an inner face upon which a knife blade may be secured, said body also having a second pair of side walls formed separately from said end walls and having bevelled ends adapted

30 to interengage with correspondingly bevelled surfaces on the adjacent sides of the end walls, said second pair of side walls also providing clamping surfaces for knife blades, and means for detachably securing said second pair of side walls between said end walls.

35

5. A cutter head of the character described comprising a hollow body having a pair of end walls and a pair of side walls formed integral with the end walls at opposite sides of the head, each of said side walls

40

6. A cutter head comprising a hollow body generally cylindrical in form and providing a substantially rectangular chamber therein, the walls of which are disposed approximately tangentially of the head, and clamping bolts entered radially through the side walls of said body and adapted to clamp cutting blades upon the inner faces of said walls, there being narrow slots in the body through which said blades may project beyond the outer periphery of the body.

55

7. A cutter head comprising a hollow body having rigid end and side walls and adapted to be mounted on a supporting spindle, cutting blades having their inner ends lying within the body and their outer ends projecting therefrom, there being

60 openings in the body to permit the blades to pass therethrough, and clamping bolts entered through said blades and the side walls of the body for clamping the blades rigidly to said side walls, said bolts having integral heads disposed between the spindle and the blades and being arranged for limited movement inwardly of the body when the cutter head is mounted upon the spindle.
